Primary Examiner — Barbara Fox*Assistant Examiner* — Kristin E Reed(74) *Attorney, Agent, or Firm* — Russell D. Nugent; The Humphries Law Firm, P.C.(57) **CLAIM**

The ornamental design for a door knocker, as shown and described.

DESCRIPTION

FIG. 1 is a top perspective view of a door knocker showing my new design;

FIG. 2 is a rear elevational view thereof;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a bottom perspective view thereof; and,

FIG. 9 is a left, perspective view thereof.

FIGS. 1 through 9 illustrate a door knocker. The broken lines shown in the figures depict portions of the door knocker that form no part of the claimed design.

1 Claim, 6 Drawing Sheets(56)
